RICHARD M. VAN VALKENBURGH AND CLARENCE A. CEDERLEAF, OF KANSAS CITY, MISSOURI, ASSIGNEES, BY MESNE ASSIGNMENTS, TO WILSON-JONES COMPANY, OF CHICAGO, ILLINOIS, A CORPORATION OF MASSACHUSETTS

LOOSE LEAF BINDER

Application filed January 24, 1927. Serial No. 163,073.

This invention relates to loose leaf binders and has for its primary object the provision of means for precluding the locking or unlocking of the mechanism therein, said 5 means being movable to the operative position only after the locking mechanism of the binder is in the locked position.

In particular this invention pertains to loose leaf binders having a hollow sheet engaging 10 member which carries mechanism therein for locking the same to the posts of the binder, which mechanism is actuated by a suitable tool insertible through the end of the hollow sheet engaging member and it is 15 another object of the instant invention to combine an auxiliary lock with the mechanism and sheet engaging member which will operate only after the post engaging mechanism has been moved to the post engaged position, said auxiliary lock thereby serving 20 the additional purpose of a signal to the operator to indicate the position of said mechanism.

An even further object of this invention is 25 the provision of a separable key actuated means for precluding the unlocking of the post engaging mechanism of a loose leaf binder, said means being inoperable until and unless said locking mechanism is in the 30 locked position.

A yet further object of this invention is to 35 provide inexpensive, strong and durable apparatus for carrying out the above objects which may be combined with the well known loose leaf binder of the end lock type and 40 which may be included in any binder of this character without prohibitive additional expense.

Minor objects will appear during the 45 course of the following detailed specification referring to but one form of embodiment of the invention shown in the accompanying drawings in which:

Figure 1 is a longitudinal central section 50 taken through the hollow sheet engaging member of a loose leaf binder, showing the auxiliary lock in place adjacent one end;

Fig. 2 is a vertical longitudinal section of the same;

Fig. 3 is an enlarged cross section taken

on line III—III of Fig. 2, looking in the direction of the arrow;

Fig. 4 is a like section taken on line IV—IV of Fig. 2; and

Fig. 5 is an enlarged perspective detail of 55 the auxiliary lock, showing it in place on the end of the post engaging mechanism, parts being broken away to show the actuating screw for said mechanism.

Similar reference characters refer to like 60 parts throughout the several views and the numerals 6 and 7 designate the two well known hollow sheet engaging members respectively of a loose leaf binder, one of which carries a plurality of posts 8 adapted 65 to receive the binder sheets not here shown. The other of said sheet engaging members designated by the numeral 7 may be termed the "follower" and as is customary is provided with openings 9 through which pass 70 the posts 8. It is well known in the art that mechanism is carried within member 7 to engage posts 8 whereby further movement along the same is precluded.

In the instance shown, this mechanism is of 75 the end lock type and comprises a longitudinally movable bar 10 having an elliptical opening 12 through which one of the posts 8 passes. In this instance, the binder has but two posts and the other passes upwardly 80 through the plate 13 which is movably supported by plate 10 and through which a like elliptical opening 14 passes to accommodate the other post 8. Plate 10 carries a screw 85 threaded actuating elements 15 which engages plate 13 to move it toward and from post 8. This element 15 is actuated through the use of the ordinary key which is inserted through an opening 16 formed in the end cap 17 fitted over the end of sheet engaging member 7. Figures 1 and 2 illustrate the mechanism in the post engaging position after the element 15 has forced plate 13 against the 90 adjacent post 8 and has pulled bar 10 so that the other post is engaged by one edge of 95 the elliptical opening 12. This action is well known in end lock binders and takes place by virtue of the fact that element 15 is screw threaded through bar 10 as shown in Fig. 2.

To this point, the binder structure is well 100

known and that part of the same which is made in accordance with this invention includes an auxiliary lock which is adapted to be moved into place only after the screw threaded element 15 has been actuated to move the locking mechanism into the locked position. This auxiliary lock may consist of a guide member 18 held in place by attachment to that end of bar 10 supporting screw threaded element 15. This guide member should extend nearly to the end cap 17 when the mechanism is in the post engaging position. It is formed to provide a barrel 19 the outer end of which terminates in a registered relation with opening 16 in end cap 17, the other end of which houses the key engaging end of the element 15. A longitudinal slot 20 is formed along one side of the guide member 18 which communicates 20 with the barrel 19 in such a way that the cylinder lock 21 may be inserted. This cylinder lock is a well known article of manufacture and may or may not be altered slightly to accommodate the conditions met in binders of different size.

After the post engaging mechanism has been moved to the post locking position, element 15 has been screwed out of barrel 19 as far as it will go and the space between the 30 squared end of the element 15 and the end cap is just great enough to permit the insertion of the cylinder lock 21. After this cylinder lock has been inserted, its key may be turned to swing its lug 22 upwardly to 35 engage the slot 23 formed in the guide member 18 and its barrel 19. When the lock 22 has reached the position shown in Figures 1 and 2, the cylinder lock key may be removed and the post engaging mechanism cannot 40 be moved to the unlocked position.

Manifestly if an attempt were made to insert cylinder lock 21 in the barrel and guide member 19 and 18 respectively before the screw threaded element 15 had been screwed in to the post locking position, the limit of inward movement would be reached before lug 22 would register with the slot 23. The key to the cylinder lock therefore could not be turned and an indication would at once be 45 set up that the post engaging mechanism had not been moved to the post engaged position. This is one of the important features of the invention and is highly valuable in post binders of the end lock type. Obviously it would 50 be impossible to insert and lock this auxiliary cylinder lock 21 before the user had actuated the post locking mechanism to the desired 55 position. The guide member has here been shown rigidly secured to one end of bar 10, 60 but it is understood that many modifications to the extent of changing the point of attachment may be made without departing from the spirit of the invention and scope 65 of the appended claims.

Having thus described the invention, what

is claimed as new and desired to secure by Letters Patent is:

1. In a loose leaf binder, a sheet-engaging member, a post passing therethrough, a locking member mounted in said first member for engaging said post, a guide member carried by said sheet-engaging member, a key-actuated device for operating said locking member longitudinally movable in said guide member, and a lock removably disposed in said guide member adjacent and in the path of said device when the locking member is in engagement with the post, said lock being formed so as to be only insertable in a locked position when said post is engaged by said locking member.

2. In a loose leaf binder, a sheet-engaging member, a plurality of stationary posts secured to and extending from said member, a second sheet-engaging member having apertures for receiving said posts, locking means carried by said second member for engagement with said posts, rotatable means disposed in said second member for actuating said last-mentioned means to engage said post for locking said second member thereon and auxiliary locking means 90 slideable in said second member for locking said rotatable means against operation, said auxiliary locking means being formed so as to be only slideable to a locked position when said first means engages said post.

3. In a loose leaf binder, a plurality of sheet-engaging members, posts rigidly secured to one of said members and projecting through the other of said members, locking means carried by one of said members contacting with said posts for preventing movement of said member thereon, and auxiliary locking means operable only when said first 100 last member and positioned adjacent one end of said first locking means, said auxiliary locking means operable only when said first locking means is in a locked position.

4. In a loose leaf binder, a sheet-engaging member, a plurality of impaling posts extending therethrough, a guide member carried by said sheet engaging member, means movably mounted in said sheet-engaging member adjacent one end of said guide member for locking said sheet-engaging member on said posts, and auxiliary locking means 105 slideable into said guide member adjacent said first means for precluding movement of the latter when said sheet-engaging member is in locked position.

5. In a loose leaf binder, a plurality of sheet-holding posts, a hollow sheet-engaging member slidably disposed on said posts, locking means therein engaging said posts for precluding movement of said member with respect to said posts, and a removable lock disposed in one end of said member adjacent 115 and in the path of the locking means, said 120

lock being actuated to a locked position when said locking means engages said posts.

6. In a loose leaf binder, a sheet-engaging member, a plurality of impaling posts extending therethrough, a guide element disposed in one end of said member, a slideable bar positioned in said member adjacent said guide, rotatable means in said member for actuating said bar to engage one of said 10 posts, and auxiliary locking means inserted into said guide element adjacent said rotatable means for precluding movement of the latter when said bar engages said post.

7. In a loose leaf binder, a sheet-engaging member, a plurality of impaling posts extending therethrough, means mounted in said member for engaging one of said posts, rotatable means in said member for actuating said first means to engage said post for locking 20 said member to said post, a guide member positioned in said sheet-engaging member, and auxiliary locking means in said guide member adjacent said rotatable means for precluding actuation of the latter when said first member 25 is locked to said post.

8. In a loose leaf binder, a sheet-engaging member, a plurality of posts passing therethrough, means carried by said member and engaging said posts for locking the member 30 thereon, a tubular guide member disposed in said first member, said guide member having a locking recess therein, and auxiliary locking means positioned in said guide member adjacent one end of said first means, said auxiliary locking means including a barrel lock 35 having a locking lug coating with said locking recess for precluding actuation of said first means from engagement with said posts.

9. In a loose leaf binder, a sheet-engaging 40 member, a post passing therethrough, a lock housing positioned in said member, and a double locking means in said housing, one of which is formed to lockingly engage the post and the other of which is formed to cooperate 45 with said housing to lock said first locking means against operation when it is in engagement with said post.

10. In a loose leaf binder, a sheet-engaging member, a second sheet-engaging member 50 cooperating with said first member, a binder post secured to said second member and passing through said first member, a main locking member carried by said first member movable to and from engagement with said post, a key actuated device for operating said locking member mounted in said first member, and an auxiliary locking member removably positioned in said first member adjacent one end of said device for precluding actuation 55 thereof.

11. In a loose leaf binder, a sheet-engaging member, a post passing therethrough, a locking member in said sheet-engaging member movable to and from engagement with said post, a rotatable actuating device for oper- 60

ating said locking member, a guide element positioned in said sheet-engaging member adjacent said locking member, and auxiliary locking means disposed in said guide element for preventing movement of the locking 70 member.

In testimony whereof we have hereunto affixed our signatures.

RICHARD M. VAN VALKENBURGH.

CLARENCE A. CEDERLEAF.
